UNITED STATES PATENT OFFICE.

GEORGE W. MULLER, OF WASHINGTON, DISTRICT OF COLUMBIA, ASSIGNOR TO MULLER RAILWAY TRACK SYSTEMS, INCORPORATED, OF WILMINGTON, DELAWARE, A CORPORATION OF DELAWARE.

BAR PLATE OR RAIL-JOINT BAR.

Application filed May 18, 1928. Serial No. 278,766.

This invention relates to bar plates or rail joint bars, sometimes termed fishplates, applied to the side of railway track rails for the purpose of holding the rails end to end where they meet and maintaining them on a level and in line.

An object of this invention is the production of a bar plate of the nature and for the purpose stated having parts specially formed and arranged whereby it is believed the rail joints may serve a longer time and be better supported on the level and in alignment than by any devices for like uses with which this applicant is familiar.

15 As exemplifying the objects of this invention, it may be stated here that bar plates constructed and arranged in accordance with this invention have been applied to main line track rails of a Class 1 railroad, where more than fifty trains daily have passed over the bars during the past five months. This traffic reached a total of more than six thousand trains and an estimated wheel load aggregating five million tons. It is an object of this invention to provide bar plates that will successfully withstand such actual service as those employed as stated have been found to do.

It is also an object of this invention to 30 make a bar of special metal having such form and structure that it will be when placed in position at all times under tension vertically and horizontally.

Another object of this invention is the 35 construction of a bar plate that upon the approach of the wheel loads will re-act and hold the joint up thus carrying the wheel across the open line between the rails with a resilient and flexible rebound.

40 Another object of this invention is the fashioning of a bar plate that when in position is always under tension, so that an outward pressure is constantly exerted against the nut and the bolt head and shank which 45 prevents them from working loose, and at the same time equally holds the bar against displacement in any direction.

To determine the preferred form bars made in accordance with this invention were 50 subjected to three hundred tons pressure edgewise, the bar being set up in its regular and intended position. As the pressure was

released the bar jumped upwardly a foot or more on the press thus proving its spring quality vertically. Bars made in accordance 55 with this invention were then tested by laying the bar down on its flat side, the part that hugs the web, on the table and a steel block three-fourths of an inch thick was placed under the end of the bar. Like pressure of three hundred tons was applied, and when released the bar re-acted springing 60 from the table.

It is also an object of this invention to 65 permit bars to be manufactured cheaply in accordance therewith of any size usable with railway rails of any size or weight.

So far as the knowledge of this applicant extends, bars of present day or ordinary type are rolled from hot billets and fit 70 under a small outer part of the rail head or throat, the rail head bearing or resting down on a part of the bar plate on its top edge throughout its length and leaving a space between the bar and the web. The 75 wave motion in the rails causes a lever action by such bars as they are now applied to the joints which wears the rails under the heads at the joints and on the top edge of the bar at the joints at the same time. 80 This wave or lever action wears the underside of bolt heads and causes the head to wear into the side of the bar plate or this lever action in the rail causes these bolts to elongate and lose their grip or tension and 85 the plates get loose and slip down on the flange of the rails. The bolts are tightened over and over again and the abrasion in the bar and under the rail head causes repeated looseness of the bolts and bar plates. 90 Another main reason of the present type bar getting loose is because they are rolled through and are one thickness and width from one end to the other and when applied to the rail they have a dead, paralyzed or 95 a sluggish action in contact with the rail and the wear on them as above described makes it impossible for it to have tension both vertical and horizontal which is very essential in holding the joints.

100 In the accompanying drawings illustrating this invention, Figure 1 presents a side view of two rails meeting end to end and having this invention applied thereto.

Figure 2 is a view of the back side of this invention which is placed against the rail.

Figure 3 is a section lengthwise of the parts as shown in Figure 1 when placed 5 against both sides of a rail the section being taken on the broken line 3—3 of that figure.

Figure 4 is a section as in Figure 3 taken on the broken line 4—4 of Figure 1.

Figure 5 is a section as in Figure 3 taken 10 on the broken line 5—5 in Figure 1, just below the head of the rail.

Figure 6, is a side view of two rails placed end to end with holes through the webs of the rails, some of the holes being 15 oval in form, vertically.

Figure 7, is a vertical section on the broken line 6—6, of Figure 1.

Figure 8 is a vertical section on the broken line 8—8 of Figure 1.

Figure 9 is a vertical section on the broken line 9—9 of Figure 1.

Figure 10 is a vertical section on the broken line 10—10 of Figure 1.

Figure 11 is a side view of two meeting 25 rails showing a modified form of this invention. In this figure a bolt hole is shown for passing a bolt between the ends of the rails, whereby the two bar plates may be held to a rail joint with 3 bolts.

Figure 12 is a side view of two meeting rails showing the bar plates secured by passing bolts, not shown, through holes located 30 near the ends of the bar, one hole at either end, whereby the bar may be held with 35 two bolts to a rail joint.

Figure 13 is a sectional view on a horizontal plane showing the web of a rail and bars formed in accordance with this invention, with a bolt passing through the 40 thickened middle portions of the bars and through the rail.

Figure 14 is a sectional view on a horizontal plane showing the web of a rail and bars formed in accordance with this invention, with the bolt passing through the bars 45 near their ends, and through the web of the rail. In this figure the bolt is shown when first tightened to draw the ends of the bars inward and upward to the rail. Figures 13 and 14 are representations of the parts illustrated substantially half size, and the views are fragmentary figures.

Figure 15, is a longitudinal sectional view showing all the parts assembled, when the 55 ends are drawn inward to an extreme final position against the web of the rail the bars at all times having tension and bolts likewise as shown.

Figure 16, shows a half full size vertical 60 or cross section on the broken line 16—16 of Figure 1, illustrating the position of the bolt when first applied and slightly tightened and before drawing the ends of the bars inward to the rail web. The bolt hole 65 15 is one of the oval holes, and to clear the

top side of the body of the bolt so that when the bolt is tightened and the bars are pulled inward and upward at their ends the bolt will have clearance in order that the joint or bar ends can be raised.

Throughout the drawings and description the same number is employed to refer to the same part.

Considering the drawings, Figure 1 shows the rails 1 and 2 with the bar plate 3, in accordance with this invention, placed across the meeting line of the rails and upon the flanges of the rails. In this Figure 1 is shown also the thickened middle portion 4 of the bar, with the added reinforce 5 increasing downwardly in length and thickness. The ends of the bar are designated 6 and 7, and their upper edges 8 and 9 are dropped somewhat below the under surface of the heads of the rails. The bar has the end flanges 10 and 11 resting upon the flanges of the rails, and these flanges may have vertical strengthening ribs 12 and 13. Bolt holes 14 and 15 pass through the bar. The two middle holes are slightly higher than the two end holes and it will be observed that the hole 15 is oval or oblong and wider at their mouth tapering inwards towards the rail.

In Figure 2 the side of the bar next to the rail is shown, and its middle thick portion is longest at the tap.

In Figure 3 the middle thickened and reinforced portions are shown together with the end portions or wings which before being clamped to the rail are spaced from the web of the rail at a gradually increasing distance from the terminations of the thickened middle portions.

Figure 4 illustrates the lower portions of 105 the middle and end portions of the bar, before being clamped to the web of the rail.

Figure 5 shows the tops of the middle thickened portions of the bar arranged against the web of the rail.

Figure 6 shows two meeting rails and the arrangement of bolt holes that may be made to engage the bars of this invention. Some of the holes are of oval form. This invention is in no way limited to the number or 115 form of the bolt holes.

Figures 7, 8, 9, and 10 show vertical sections of the positions of different parts of the bar plate with respect to the head and web and flange of the rail, before the bolts are inserted and made tight. The form of the thickened middle portion and of its reinforce added portion is shown in the Figure 10.

In Figure 11 there are shown two meeting 125 rails 16 and 17 with a modified bar 18 arranged against the sides of the rails. The bar has three bolt holes 19, 20 and 21. It will be noted that the hole 20 is slightly higher than the other holes, and that the 130

added reinforce part of the thickened middle portion 22 is now omitted to allow for the bolt head and nut. But, the rib 23 remains as before across the lower middle portion of the bar to assist in taking care of the blows and weight and to add to the strength of the bar at its bottom middle portion.

In Figure 12, the bar is shown marked 24, 10 and it has but two bolt holes 25 and 26. This modification of the bar will hold the joint in a great variety of situations. The bar joint with two holes should have extra large bolts for strength.

15 As shown in Figures 13 and 14, it is advantageous to use a bolt 27 with an enlargement or throat 28 near the head of the bolt. It will be noted that the bolt hole in the bar is tapered correspondingly with the enlargement 28, and this construction insures a perfectly tight joint whatsoever the hurry may be on the part of the track layers. It is to be understood, however, that this invention is in no way limited to any particular shape 25 of the bolts or bolt holes.

In Figure 15 where the ends of the bars have been forced into their extreme or final position against the rail web, and the bolts and bolt heads, as well as the bars themselves, are under constant tension as will be noted by the space clearing the web between the thickened middle portion and the extreme end portions of the bar plate. Wheel loads passing in any number can not shake 35 the bolts loose, and the bars re-act upwardly having a tendency to lift the load or throw the force from the joint in the same direction as the wheels of the car approaching the meeting line of the two rails or when it 40 passes over the joint to throw it beyond in the direction the wheel is moving.

In Figure 16 the rail 2 is shown in section, with the bar plates 3 clearing the sides. The bolt 29 has been tightened, or this sectional figure may be taken as a section 45 through the bar plates near their ends and the rail after the ends of the bars have been drawn inward or to the web of the rail. It will be noted that the oval bolt hole 15 in 50 the web of the rail would allow clearance of the bolt for a certain elastic bending of the bar edgewise upward or when drawn inward or tightened to its extreme, or under a heavy wheel load, or the rails bending down over 55 the bolt hole would clear the bolt and throw the pressure or weight to the joint at the thick middle portion of the bar where it is intended, and as herein before described. The bar will fully recover its first shape 60 after the load has passed and the bolts cannot work loose.

It will be understood that the bar herein specified has a cambered effect both on its top edge and back side, fitting the rail, so 65 upon the approach of the load, and when

on the joint, the rail heads and ends immediately function by the springy action or tension qualities of the bar, the direction thereof being both vertical and horizontal thereby counteracting the load or stress trial 70 location.

It is believed that the drawings so fully illustrate this invention, taken with the foregoing description, that an explanation of the operation in detail is not necessary. A 75 joint or bar plate fashioned and constructed in accordance with this invention has the effect that when the wheel load is directly over the middle of the bar or at the meeting line of the two rails, the weight is always equally 80 distributed and taken up by the bar throughout its entire length, width and thickness, and the wheel load does not throw a strain on any particular part of the bar or on any individual bolt as is now frequently the result with ordinary fishplates. When a wheel approaches a joint equipped with this invention, the ends of the rails are always supported and held up and carry the wheel 85 across the joint. The ends of the rails do not dip or batter as the action of the bar plates under the approaching wheels is to throw the joint up in a reflex action and the rail ends are brought solidly together and hold 90 themselves in a straight line. 95

Having now described this invention and explained the manner of its operation, I claim:

1. A bar plate for holding two rails end to end where they meet with the meeting line vertical and the rails in line lengthwise, said bar plate being thicker and wider through its middle portion and reinforced at the middle with additional thickened portions, the inner surface of said middle portion conforming with and facially abutting the rail web. 100

2. A bar plate for holding two rails end to end where they meet, the said bar being wider and thicker through its middle portion, and the said middle portion conforming with and snugly fitting against the side of the web of the rail and part way under the head of the rail and down upon the top 110 of the flange of the rail. 115

3. A bar plate for holding two rails end to end where they meet, the said bar being wider and thicker through its middle portion, the said middle portion being formed to fit snugly against the web and head and flange of the rail, the surface of the said bar from the terminations of the said middle thickened portions being tapered and spaced from the web of the rail, the said tapered 120 surface extending to the ends of the bar whereby the end portions of the bar are thinner than the said middle portion. 125

4. A bar plate for holding two rails end to end where they meet, the said bar being 130

- wider and thicker through its middle portion and formed to fit snugly against the web and head and flange of the rail, the surface of the bar from the terminations of the said 5 thickened portions being tapered and spaced from the web of the rail at a gradually increasing distance to the ends of the bar whereby the end portions of the bar are made thinner than the said middle portions.
- 10 5. A bar plate for holding two rails end to end where they meet with the meeting line vertical and the rails in line lengthwise, said bar being thicker and wider through its middle portion, the said middle portion being 15 greater in length at the top than at the bottom and having its inner surface shaped in conformity and adapted for facial abutment with contiguous portions of the rail web, head and base flange, and the said middle 20 portion having at the middle thereof an additional thickened portion.
6. A bar plate for holding two rails end to end where they meet, the said bar being wider and thicker through its middle portion, the said middle portion being greater 25 in length at the top than at the bottom, and the said middle portion conforming with and snugly fitting against the side of the web of the rail and part way under the head of the 30 rail and down upon the top of the flange of the rail.
7. A bar plate for holding two rails end to end where they meet, the said bar being wider and thicker through its middle portion, the said middle portion being formed 35 to fit snugly against the web and head and flange of the rail, the side of said thickened portion formed to fit the rail being longer at the top than at the bottom, and the ends 40 of the said bar plate from the terminations of the said thickened middle portions being tapered and spaced from the web of the rail when in position on a rail.
8. A bar plate for holding two rails end 45 to end where they meet, the said bar being wider and thicker through its middle portion and formed to fit snugly against the web and head and flange of the rail, the ends of the said bar plate from the terminations 50 of the said middle thickened portions being tapered and spaced from the web of the rail when in position on a rail at a gradually increasing distance to the ends of the bar whereby the end portions of the bar are 55 made thinner than the said middle portions.
9. A bar plate for holding two rails end to end where they meet, the middle portion of the said bar plate being made wider and thicker, and the end portions of the bar 60 from the terminations of the middle portion being thinner and spaced from the web of the rail when in position thereon, the bottoms of the said end portions resting down upon the top of the flange of the rail.
10. A bar plate for holding two rails end to end where they meet, the middle portion of the bar being made wider and thicker than the end portions, the side of the said middle portion resting against the rail when in position thereon being longer at the top 70 than at the bottom, and the end portions of the bar diminishing in thickness to their extremities.
11. A bar plate for holding two rails end to end where they meet, the middle portion of the bar being made wider and thicker than the end portions, said end portions diminishing in thickness outwardly, the top edges of the said end portions dropping down below the top of the middle portion to clear the under side of the head of the rail, and the bottom edges of the said end portions constructed to rest down on the top of the flange of the rail when in position thereon. 75
12. A bar plate for holding two rails end to end where they meet, the middle portion of the bar being made wider and thicker than the end portions, the side of said middle portion resting against the rail when in position thereon being longer at the top than 80 at the bottom, the said middle portion having a reinforce added portion at its middle part increasing in width and thickness from top to bottom thereof. 85
13. A bar plate for holding two rails end to end where they meet, the middle portion of the bar being made wider and thicker than the end portions, the side of said middle portion resting against the rail when in position thereon being longer at the top 90 than at the bottom, the said middle portion having a reinforce added portion at its middle part, and the said added portion having a reinforce rib at its bottom extending lengthwise of the said bar above the flange 95 of the rail. 100
14. A bar plate for holding two rails end to end where they meet, the middle portion of the bar being made wider and thicker than the end portions, the said bar being provided with bolt holes through the said middle portions and near the extremities of the end portions, the end portions being spaced from the web of the rail when in position thereon, whereby the middle portion 110 of the bar rests against the rail and the ends of the end portions only are in contact with the rail. 115
15. A bar plate of the character described, the middle portion of the bar being made relatively thick, the ends of the bar being resilient, and the said bar having a plurality of bolt holes through it a part of the number of said holes being of oval form in cross-section. 120
16. A bar plate of the character described having its middle portion relatively thickest, the bar having resilient end portions diminishing in thickness to their extremities, and the said bar having a plurality of bolt holes, 125 130

a part of the said holes being oval diminishing in diameter from the outer to the inner face of the bar.

17. A bar plate of the character described having its middle portion relatively thickest, the bar having resilient end portions diminishing in thickness to their extremities and normally having their extremities only in

contact with the web of the rail when in position thereon, and the said bar being supported upon the flanges of the rails by base flanges located at the bottom of the said middle portion of the bar and at the bottoms of the extremities of the said end portions.

In testimony whereof I affix my signature.
GEORGE W. MULLER.
